(57) **CLAIM**

The ornamental design for a case design for a wireless processing/sensing unit, as shown and described.

<

DESCRIPTION

The ornamental design is for a case intended to contain wireless network devices. The devices include independent processing and sensing capabilities, suitable for placement in a variety of locations and environments to gather sensed information and report it on a network. The ornamental nature of the case provides for a distinctive appearance.

FIG. 1 is a top view of the case of the present design, defining top, bottom, left and right sides for drawings 2—6.

FIG. 2 is a bottom right side perspective of the present design.

FIG. 3 is a top left side perspective of the present design.

FIG. 4 is a bottom side view of the present design.

FIG. 5 is a top side view of the present design; and,

FIG. 6 is a bottom right corner perspective of the present design.

The broken lines showing additional features of the case design are for illustrative purposes only and form no part of the claimed design.
